FRANK SPALDING, OF PROVIDENCE, RHODE ISLAND, ASSIGNOR TO
BROWN & SHARPE MANUFACTURING COMPANY, OF PROVIDENCE,
RHODE ISLAND.

COMBINATION-TOOL.

SPECIFICATION forming part of Letters Patent No. 769,196, dated September 6, 1904.

Application filed July 24, 1902. Serial No. 116,790. (No model.)

To all whom it may concern:

Be it known that I, FRANK SPALDING, a citizen of the United States, residing at Providence, in the county of Providence and State 5 of Rhode Island, have invented a new and useful Improvement in Combination-Tools, of which the following is a specification.

This invention has reference to an improvement in a combination-tool constructed to be 10 adapted for a number of different purposes.

The invention consists in the peculiar and novel construction of a try-square and the combination with the same of parts whereby the try-square may form the essential part of 15 a depth-gage, a centering-gage, and a surface-gage, retain its use as a try-square, and possess other convenient uses, as will be more fully set forth hereinafter.

Figure 1 is a side view of the tool, showing 20 the same adapted for a depth and a surface gage. Fig. 2 is a front view of the same. Fig. 3 is a top view, partly in section, of the surface-gage attachment. Fig. 4 is a vertical sectional view of the same. Fig. 5 is a horizontal sectional view of the head of the try-square. Fig. 6 is a plan view of the detachable base, and Fig. 7 is a transverse sectional view on the line 7 7 of Fig. 6 of the same. Fig. 8 is a side view of the center-gage, showing 25 the same attached to the blade of the try-square; and Fig. 9 is a sectional view on the line 9 9 of Fig. 8. Fig. 10 is an enlarged side view of the scratch-pin inserted in the head of the try-square.

Similar marks of reference indicate corresponding parts in all the figures.

In the drawings, A indicates the head of the try-square, which is provided with three bearing-faces—the base-face a , the front face a' , and the miter-face a'' . The head A has the opening a^3 , in which the clamp nut a^4 is operated to bear on the tubular boss a^5 , in which the screw a^6 , provided with an extension terminating in the bead a^7 , slides. The head A has also the semicircular opening a^8 . The partly-cut-away level-tube a^9 is placed so that the bulb of the mercurial bevel may be seen. A tube for the reception of the scratch-pin a^{10} is also provided.

The front face a' of the head A is slotted to 50 receive the blade B, which is graduated, preferably, on both sides and has the groove b extending on one side, preferably on the center line, from end to end of the blade. The blade B fits the slot in the front a' of the head A 55 with a sliding fit. The bead a^7 fits the groove b with a close sliding fit. The inner edge of the blade B bears against the bottom of the groove, being held against the same by the spiral spring in the sleeve of the nut a^4 , so 60 that the blade B may be drawn through the slot and may be secured to the head by turning the nut a^4 on the screw a^6 to clamp the blade, as is shown in Fig. 5. When the blade B is drawn out to project beyond the face a of 65 the head A, as shown in Fig. 1, the blade and the face a form a true square, while the blade and the face a' form a true miter and may form any desired angle. With the use of the level the edges of the blade B may be used to 70 indicate true, vertical, or plumb lines.

To adapt the try-square to use as an accurate depth-gage, I provide the base C of considerably greater width than the face a of the head A to insure a true bearing. I form in 75 the base C the groove c , into which the face a accurately fits, and preferably deepen the center of the groove c , as shown in Figs. 6 and 7, to give to the face a a sliding bearing only. I secure the head A in the base C by 80 means of the clamp-plate c' , connected by the dowel c^2 with the base and raised off from the base by the spiral spring c^3 . The thumb-screw c^4 in screw-thread engagement with the base bears on the clamp-plate c' , and by 85 it the end of the plate c' is forced against the edge of the face a to firmly secure the head of the try-square to the base. When the blade B is adjusted to project through the slot c^5 the desired length below the base C, 90 the depth of a groove or depression may be accurately measured.

When the combination-tool is to be used as a surface-gage, the head A is preferably secured in the base C as above described; but 95 the blade B is adjusted so that one end of the blade is on a line with the lower surface of the base, and the surface-gage attachment D

is adjusted on and secured to the blade B. The surface-gage attachment D consists of the arm d, having the slot d' with the raised bead d² on one side, the said bead engaging with 5 the groove b of the blade B. The bar d³, controlled by the thumb-screw d⁴, serves to clamp the blade B in the adjusted position and securely support the surface-gage. The post d⁵ extends transversely through the arm 10 d, the head of the post bearing against one side of the arm. The thumb-screw d⁴ extends transversely through the post d⁵. On the projecting portion of the post d⁵ are supported the base-disk d⁶, the spring-disk d⁷, and 15 the milled disk d⁸. The milled disk d⁸ is provided with a sleeve on which the spring-disk d⁷ is rotatably supported. The pointer d⁹ is supported in a groove in the spring-disk d⁷. The end of the post d⁵ is screw-threaded and 20 is in screw-thread engagement with the thumb-nut d¹⁰, which bears against a washer. A coiled spiral spring is interposed between the washer and the thumb-nut d¹⁰. By loosening the thumb-nut d¹⁰ the pointer d⁹ may 25 be adjusted longitudinally and the spring-disk may be turned to adjust the pointer, and the whole may be secured in the adjusted position by tightening the thumb-nut.

When it is desired to find the center of a 30 round article, the center-gage E is secured to the blade B, as shown in Figs. 8 and 9. The center-gage has the slotted base e with the transverse tubular boss e', in which the bolt e² may move with a close sliding fit. The end 35 e³ of the bolt is screw-threaded and is in screw-thread engagement with the nut e⁴, which is cushioned by a spiral spring interposed between the nut and the end of the tubular boss. An extension of the bolt e² is provided with 40 the raised bead e⁵, which engages with the groove b on the blade B. From the base e extend the oblique arms e⁶ and e⁷, preferably placed at an angle of ninety degrees to each other and at forty-five degrees to the edges 45 of the blade B. The center-gage E when connected with the blade B is held in frictional contact with the same by the coiled spring acting on the nut e⁴ and may be firmly secured by tightening the nut.

The combination-tool materially facilitates 50 the taking of measurements and the work of machinists attending planing, grinding, and other machines requiring frequent and accurate measurements.

Having thus described my invention, I claim 55 as new and desire to secure by Letters Patent—

1. In a tool of the nature described, the combination with the slotted head of the try-square, means for securing the try-square to the grooved blade, the enlarged base, means 60 for securing the head to the enlarged base of the try-square, and the longitudinally-grooved blade, of the slotted arm d, the bead d² in the slot, the post d⁵, the rotatably-supported disk d⁷, the pointer d⁹, and means for securing the 65 pointer, as described.

2. In a tool of the nature described, the combination with a grooved blade B, of the try-square A having the faces a' and a², means for securing the try-square to the grooved 70 blade B, the removable base C, and means for securing the base to the face a of the try-square consisting of the clamp-plate and thumb-screw, as described.

3. In a tool of the nature described, the combination with the grooved blade B, the try-square A, means for securing the try-square to the blade, consisting of the screw d⁶ having the bead d⁷ and the clamp-nut d⁴, the removable base C, means for securing the base 80 C to the try-square, consisting of the clamp-plate c' and the thumb-screw c¹, of the arm d, means for securing the arm in the adjusted position to the grooved blade B, consisting of the thumb-screw d⁴, the post d⁵, the base-disk 85 d⁶, the spring-disk d⁷ carrying the pointer d⁹, the milled disk d⁸, and the thumb-nut d¹⁰ in screw-thread connection with the post, whereby the pointer is clamped and held in the adjusted position, as described. 90

In testimony whereof I have signed my name to this specification in the presence of two subscribing witnesses.

FRANK SPALDING.
